CLAIM

I claim the ornamental design for a grating device, as shown and described.

DESCRIPTION

FIG. 1 is a left side view of my design for a grating device, the right side view being identical;

FIG. 2 is a front view of the design for the grating device shown in FIG. 1;

FIG. 3 is a rear view of the design for the grating device shown in FIG. 1;

FIG. 4 is a top view of the design for the grating device shown in FIG. 1; and,

FIG. 5 is a bottom view of the design for the grating device shown in FIG. 1.

A magnified view of the grating surface pattern of the grating device shown in FIGS. 1-5 is shown in FIG. 1.

1 Claim, 2 Drawing Sheets
